SOLE FLEXING MACHINE

Napoleon A. Monfils, Haverhill, Mass., assignor to
 United Shoe Machinery Corporation, Flemington N. J., a corporation of New Jersey

Application March 3, 1941, Serial No. 381,435

13 Claims. (Cl. 12—41.2)

This invention relates to machines for mechanically reducing the stiffness of unattached leather soles. The invention is embodied in an improved organization that works the leather to loosen its fibrous texture without cutting or rupturing its fibers.

One novel feature of the invention consists in an improved arrangement of a series of three cooperative rolls two of which are arranged to wrap a portion of a sole repeatedly around a segment of an intermediate anvil-roll but to yield, if necessary, instead of compelling the sole to submit to the maximum bending before it is sufficiently pliable to do so without being ruptured.

Another novel feature consists in an organization in which depression of a treadle will bring the anvil-roll and the wrapping rolls into a cooperative relation after a sole has been interposed between them, and in which an operating mechanism will thereafter produce relative reciprocation of the anvil-roll and the wrapping rolls to effect successive wrapping operations. This feature provides for flexing a sole between its ends without flexing either of its ends and without stubbing the sole against any roll while inserting it between the rolls.

Still another novel feature consists in providing a power-operated wrapping or flexing mechanism with a starting and stopping means under control of the aforesaid treadle, to the end that the wrapping mechanism will be brought into operation only when, and in consequence of, bringing the anvil-roll and the wrapping rolls into their cooperative relation. This feature not only avoids wasting power when the rolls are separated, but it also facilitates insertion of the soles because all the rolls remain stationary when they are separated.

The invention also provides power-driven means for rotating one of the rolls (the anvil-roll) to feed out a sole in process of being worked. The rolls produce a novel feeding effect the force of which is not fully developed until a sole is so closely wrapped around the power-driven roll as to have its maximum area of contact therewith. Consequently, if a sole is initially too stiff to be so wrapped, the operator may, by resisting the underdeveloped feeding force, prevent the sole from advancing until two or more flexures localized in one area of the sole have broken down the stiffness in that area to a degree that enables the flexed area to be closely wrapped. Then, since the coefficient of friction between the driven roll and the flexed area will have been fully developed, the sole will be advanced against

the operator's resistance to bring an unflexed area into the field of operation. This feature of the invention supplements the yielding of the wrapping rolls to provide for breaking down the initial stiffness in easy stages and to regulate the feeding in accordance with development of flexibility.

Referring to the drawings,

Fig. 1 is a left side elevation of a sole-flexing machine embodying the present invention;

Fig. 2 is a side elevation, partly in section, of the operating elements in the act of wrapping a sole around a segment of the anvil-roll;

Fig. 3 is a top plan view of the rolls and a sole in the relation shown in Fig. 2;

Fig. 4 is a side elevation, partly in section, of the clutch and an arm for controlling it;

Fig. 5 is a front elevation of the parts included in Fig. 2;

Fig. 6 is a right side elevation of the lower portion of the machine frame and a band-brake;

Fig. 7 is a top plan view, partly in section, of the starting and stopping mechanism; and

Fig. 8 is a top plan view, partly in section, of a portion of the clutch.

To present a sole 10 to the flexing mechanism the operator will hold it grain side up, grasp it by its heel end and place its toe end against an abutment 11 as shown in Fig. 1. The middle portion of the sole will then lie on an anvil-roll 12 and extend under a pair of parallel and freely rotatable flexing rolls 13. An arm formed on the abutment 11 is affixed to the frame 14 by two clamping screws 15 and is provided with slots 16 through which these screws extend. The slots permit adjusting the abutment toward and from the rolls according to the length of the soles. In practice, the abutment will be set to locate the ball-line of a sole a little off the anvil-roll 12 and at the abutment side thereof.

Having placed a sole as shown in Fig. 1, the operator starts the operation of the machine by depressing a treadle 17. This raises the anvil-roll 12 into cooperative relation with the flexing rolls 13 and trips a clutch by which the latter are set in operation to wrap the sole repeatedly around a segment of the anvil-roll.

The anvil-roll is affixed to a shaft 18 and the latter is journaled in a yoke that forms a part of a vertically movable jack or carrier 20. This carrier is arranged to slide in a guiding bracket 19 affixed to the column 21 of the frame. The carrier 20 and a toggle member 22 are connected by a pivot-pin 23. Another toggle member 24 is

mounted on a fulcrum-pin 25 in the base of the column. The toggle members are connected by a knee-pivot 26. The treadle 17 is a part of the toggle member 24. These parts are initially held in the positions represented in Fig. 1 by a pair of tension springs 27, but when the treadle is depressed the toggle members take the positions represented in Fig. 2 and remain there until the operator releases the treadle.

The flexing rolls 13 are mounted on a vertically movable carrier that remains stationary at the upper limit of its range of travel except when the treadle 17 is depressed. This carrier comprises a slide 30 and two pairs of levers all connected by a common fulcrum-pin 31. One of the flexing rolls 13 is carried by a pair of levers 32, and the other is carried by a pair of levers 33. The purpose of the levers is to provide for movement of the flexing rolls toward and from each other. The levers of one pair lie across those of the other pair, and their upper ends are connected by tension springs 34 the effect of which is to move the flexing rolls toward each other. The upper arms of the levers are held initially against stops 35 by which the flexing rolls are maintained in positions to straddle the anvil-roll.

The slide 30 is arranged in guideways 36 on the frame 14 and derives its operating motion from a mechanism comprising a link 37, a lever 38, an eccentric-rod 39 and an eccentric 40. The lever and the frame 14 are connected by a fulcrum-pin 41. The eccentric 40 is carried by a shaft 42 to which any desired number of revolutions may be imparted in each run of the machine, according to the length of time during which the treadle remains depressed. When the flexing rolls 13 are carried down they straddle the anvil-roll, as shown in Fig. 2 and if a sole is placed on the anvil-roll before the treadle is depressed it will be wrapped around the anvil-roll by the flexing rolls.

The applied force of the springs 34 may be regulated by turning nuts 43 in which screw-eyes 44 are threaded. In practice, these devices will be adjusted to permit the flexing rolls 13 to yield in some degree when their descent is resisted by a sole too stiff to be bent quite to the curvature of the anvil-roll 12. Moreover, each of the rolls 13 may yield irrespective of the other, and if they do not quite conform the sole to the curvature of the anvil-roll during one operating stroke of the slide 30 they will, at least, take some of the "fight" out of the sole and accomplish their full bending effect in another operating stroke. Their flexing effect will therefore be developed in successive stages instead of subjecting the sole to treatment so severe as to break the fibres of the leather or crack the grain thereof.

When the knee-pivot 26 of the toggle is shifted to the position shown in Fig. 2 it is carried across and slightly beyond its dead-center position which coincides with a line intersecting the pivot-pins 23 and 25. This movement of the toggle causes a pair of stop-shoulders on the member 22 to abut a pair of cheeks on the member 24. One of these shoulders is indicated at 28 in Fig. 1 and the corresponding cheek is indicated at 29. These shoulders, when seated on the cheeks, sustain the full force applied to the anvil-roll by the flexing rolls, and to that extent relieve the operator from much of the effort that would otherwise be required to support the anvil-roll in its operative position.

The machine is provided with starting and stopping mechanism so controlled as to initiate

the operation of the flexing rolls when the anvil-roll is shifted to its operative position and to terminate such operation when the anvil-roll is displaced from its operative position. To this end the shaft 42 is provided with a clutch the operation of which is controlled by the treadle 17. Referring to Fig. 7, the driving member 50 of the clutch is loosely mounted on the shaft and the driven member 51 is affixed to the shaft. A bolt 52 nested in a groove in the driven member is movable into and out of the path of a series of lugs 53 of the driving member to give effect to the clutch. A compression spring 54 (Fig. 8) is arranged to project the bolt into the path of the lugs 53 whenever the bolt is tripped by an arm 55. This arm and an arm 56 are rigidly connected by a rock-shaft 57 that extends through a bearing 58. An extremity of the arm 56 is arranged to be depressed by the treadle 17 to lift the extremity of the arm 55 out of a groove 59 in the member 51 and out of a notch in the bolt 52 (see Figs. 4 and 7). The bolt is thus tripped to set the clutch in operation. When the operator releases the treadle a tension spring 60 (Fig. 1) draws the extremity of the arm 55 into the groove 59 in the driven member of the clutch and into the path of rotation of a beveled surface 61 of the bolt 52. When this surface strikes a beveled surface 62 of the arm 55 the bolt is retracted with a wedging action and the driven member of the clutch is thus released from the driving member. The wedging action of the members 52 and 55 also has a braking effect to arrest rotation of the shaft 42, but a supplemental braking effect is provided by a drum 63, a friction band 64 and a tension spring 65 (see Fig. 6). One end of the band is anchored to the frame 21. The starting and stopping elements are so organized that the tension of the band 64 may be regulated to stop the shaft 42 when the flexing rolls 13 are at the upper limit of their range of travel, as in Fig. 1. The clutch member 50 may receive rotation from a driving belt arranged to run on its periphery, and its speed may be about 90 R. P. M.

The mechanisms hereinbefore described are sufficient to do all the flexing that a sole may require, provided the operator maintains a grasp of the heel end and draws the sole toward himself a little at a time between successive operative strokes of the flexing rolls to distribute the flexing effect through the forepart. Nevertheless, the invention includes an automatic feeding mechanism by which the sole will be slowly fed out while the machine is in operation. For this purpose the machine is provided with means for transmitting rotation from the shaft 42 to the anvil-roll 12 and for reducing the speed of rotation to shift the sole about $\frac{3}{8}$ inch for each operating stroke of the flexing rolls.

The transmission under consideration comprises a small driving sprocket 70 (Figs. 6 and 7) affixed to the shaft 42, a large driven sprocket 71, a transmission chain 72 arranged to run on them, a small driving sprocket 73, a large driven sprocket 74 (Figs. 1 and 2), and a transmission chain 75 arranged to run on the latter pair of sprockets. The sprocket 74 is affixed to the shaft 18 of the anvil-roll. The sprockets 71 and 73 are affixed to each other and both rotatable on a supporting stud 76 affixed to the frame 14. An arrow adjacent to the anvil-roll in Fig. 1 indicates the direction of rotation of that roll when the treadle is depressed.

The anvil-roll may be made of wood or metal and it has a smooth periphery to be engaged

by the flesh side of a sole. The two flexing rolls may also be made of wood or metal and have smooth peripheries for engaging the grain side of a sole.

The toggle member 22 (Figs. 1 and 2) has an adjustable connection 17 by which its effective length may be regulated to cause a sole to be gripped by the three rolls when the toggle is straightened and the flexing rolls are at their highest level. A portion of the sole is thus deflected between the flexing rolls by a segment of the anvil-roll. The tractive effect of the anvil-roll is comparatively little except when the sole is wrapped closely around it. Consequently, if the operator maintains a grasp on the heel end of the sole during the flexing period, he may retard the feeding movement of the sole, particularly a very stiff one, until its stiffness has been reduced to a degree that will enable it to be wrapped closely about the anvil-roll, but when this stage of flexibility has been developed, the tractive effect of the anvil-roll will be sufficient to overcome the retarding effort of the operator.

Having thus described my invention, what I claim as new and desire to secure by Letters Patent of the United States is:

1. A sole-flexing machine comprising an anvil-roll, a pair of parallel flexing rolls arranged to cooperate therewith, said flexing rolls being movable toward and from each other, spring-biased means by which said flexing rolls are normally moved toward each other but enabled to be wedged apart by said anvil-roll, and power-operated means by which relative reciprocations of said anvil-roll and said flexing rolls are caused to wrap a portion of a sole repeatedly around a segment of said anvil-roll.

2. A sole-flexing machine as specified in claim 1 comprising also manually operable means by which relative movements of approach and separation between said anvil-roll and said flexing rolls may be effected to initiate and terminate their cooperative relation.

3. A sole-flexing machine as specified in claim 1 comprising also power-driven means by which said anvil-roll may be rotated to feed the sole in process of being flexed.

4. A sole-flexing machine as specified in claim 1 comprising also two carriers, manually operable means by which one of said carriers may be shifted toward and from the other, and power-operated means by which the other said carrier may be reciprocated with movements toward and from the carrier first specified, said anvil-roll being carried by one of said carriers and said flexing rolls being carried by the other.

5. A sole-flexing machine comprising an anvil-roll, a support therefor, a pair of parallel flexing rolls arranged to cooperate with said anvil-roll, a support for said flexing rolls, means arranged to cause said flexing rolls to wrap a portion of a sole around a segment of said anvil-roll by producing relative movement of approach and separation of said supports, said flexing rolls being movable toward and from each other, and spring-biased means by which said flexing rolls are normally moved toward each other but enabled to be wedged apart by said anvil-roll.

6. A sole-flexing machine comprising three cooperative rolls two of which are movable toward and from each other and the third of which is arranged to deflect an intermediate portion of a sole between said two, spring-biased means by

which said two rolls are normally moved toward each other but enabled to be wedged apart by said third roll, and power-operated means by which said three rolls are relatively reciprocated to shift their axes toward and from a common plane in a range that requires said two rolls to wrap a sole around a segment of said third roll.

7. A sole-flexing machine comprising a jack, an anvil-roll carried thereby, a pair of parallel flexing rolls movable toward and from each other, spring-biased means by which said flexing rolls are normally moved toward each other and initially maintained adjacent to each other, manually operable means by which said jack may be operated to shift said anvil-roll to and from an operative position where it will deflect a portion of a sole between said flexing rolls, power-operated means by which said flexing rolls may be reciprocated to wrap the sole repeatedly around a segment of said anvil-roll, and mechanism controlled by said manually operable means to start and stop said power-operated means.

8. A sole-flexing machine as specified in claim 7 comprising also power-operated means controlled by said starting-and-stopping mechanism to rotate said anvil-roll and thereby feed the sole in process of being flexed.

9. A sole-flexing machine comprising a jack and a carrier movable toward and from each other, an anvil-roll carried by said jack, a pair of flexing rolls carried by said carrier and arranged to cooperate with said anvil-roll, manually operable means arranged to operate said jack and including a toggle arranged to be straightened to maintain said anvil-roll in cooperative relation with said flexing rolls, power-operated means by which said carrier may be reciprocated to cause said flexing rolls to wrap a portion of a sole repeatedly around a segment of said anvil-roll, and mechanism for starting and stopping said power-operated means, said starting-and-stopping mechanism and said manually operable means being cooperatively related to cause operation of said flexing rolls only when said toggle is straightened.

10. A sole-flexing machine comprising an anvil-roll, a pair of flexing rolls arranged to cooperate therewith, power-operated means by which said flexing rolls may be reciprocated to wrap a sole repeatedly around a segment of said anvil-roll, and manually operable means by which said anvil-roll may be shifted into and out of cooperative relation with said flexing rolls.

11. A sole-flexing machine comprising an anvil-roll, a pair of flexing rolls arranged to cooperate therewith, power-operated means by which said anvil-roll and said flexing rolls may be relatively reciprocated to wrap a sole repeatedly around a segment of said anvil-roll, and manually operable means by which said anvil-roll and said flexing rolls may be relatively shifted into and out of cooperative relation.

12. A sole-flexing machine as specified in claim 11 comprising also spring-biased means by which said flexing rolls are normally moved toward each other with provisions for yielding away from each other within their fields of operation.

13. A sole-flexing machine as specified in claim 11 comprising also an abutment against which one end of a sole may be placed to locate an intermediate portion of the sole in the operating field of said rolls.
